P.C.(57) **CLAIM**The ornamental design for a beverage machine, as shown and
described.

DESCRIPTION

FIG. 1 is a top, front, left perspective view of a beverage
machine showing our new design;

FIG. 2 is a top, front, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate portions of the beverage machine
that form no part of the claimed design.**1 Claim, 8 Drawing Sheets****FIG. 1**
